UNITED STATES PATENT OFFICE.

SAMUEL E. SPERRY, OF WOODHAVEN, NEW YORK, ASSIGNOR TO INTERTYPE CORPORATION, OF BROOKLYN, NEW YORK, A CORPORATION OF NEW YORK.

TYPEGRAPHICAL MACHINE.

1,229,160.

Specification of Letters Patent.

Patented June 5, 1917.

Application filed October 5, 1915. Serial No. 54,226.

To all whom it may concern:

Be it known that I, SAMUEL E. SPERRY, a citizen of the United States, residing at Woodhaven, in the county of Queens and State of New York, have invented new and useful Improvements in Typographical Machines, of which the following is a specification.

My present invention relates to improvements in typographical machines, and more especially to those of the linotype class and of the type adapted to contain a plurality of magazines, and the primary object of the invention is to provide simple and improved means whereby any one of the magazines may be readily brought into operative position to deliver matrices under the control of a keyboard and the magazines may be swung into a position for convenient substitution or removal.

To these and other ends, the invention consists in certain improvements, and combinations and arrangements of parts, all as will be hereinafter more fully described, the novel features being pointed out particularly in the claims at the end of the specification.

In the accompanying drawings:—

Figure 1 is a side elevation of a portion of a machine of the linotype class embodying magazine supporting and shifting means constructed in accordance with the present invention.

Fig. 2 is a detail view, on an enlarged scale, showing devices for automatically moving the supplementary reeds and the assembler entrance to and from operative position to permit shifting of the magazines.

Fig. 3 is a view similar to Fig. 1, showing the magazines shifted into a different position.

Fig. 4 is a view similar to Fig. 3, showing the magazines swung into a position for removal.

Similar parts are designated by the same reference characters in the several views.

The present invention is applicable generally to linotype machines, although it is capable of use generally in connection with typographical machines wherein the matrices are stored in magazines from which the matrices are delivered to the assembling line under the control of a keyboard. The preferred embodiment of the invention is

shown in the present instance, but it is to be understood that modifications or changes may be made, and that equivalent constructions within the scope of the claims are contemplated.

In the present instance, 1 represents the upper portion of the main frame of the machine, and 2 represents a magazine carrying frame. In the construction shown, the frame 2 is adapted to contain three magazines 3, 4 and 5, the magazines being removably mounted in the frame 2 and they are preferably arranged with their forward ends spaced in close relation and their rear ends more widely spaced in order that the overhang of the magazines at the front of the machine may be reduced and ample space provided at the rear of the magazines to accommodate matrix retaining shutters. As shown, the forward end of each magazine is provided with a series of escapements 6 which controls the delivery of matrices from the respective magazine, and 7 designates the reeds which are actuated by manipulation of the keyboard. The keyboard, together with the actuating reeds 7, may be of the type commonly used in machines of the linotype class. The matrices delivered from the particular magazine in use pass through an assembler entrance 8 on their way to the assembling point. In the present instance, this assembler entrance is slideable or otherwise movable vertically to carry its upper end either into a position to coöperate with the lower or forward end of the particular magazine in use or into a position where it will clear the magazines and thereby permit shifting of the magazines without obstruction. In the construction shown, this assembler entrance is shiftable vertically on its guide 9, and a tension spring 10 operates thereon to raise the assembler entrance or to move the assembler entrance into coöperative relation with the magazine which is in operative position.

The main frame of the machine is provided at each side with a supporting projection 11, which is preferably provided with a roller 12. The magazine carrying frame 2 is provided with a supporting surface 13 adapted to travel over the respective roller 12, and this supporting surface 13 is provided with a suitable number of appropriately located notches, recesses or depre-

sions in which the roller 12 is adapted to rest. In the present instance, three magazines are used and, hence, there are three notches, recesses or depressions 14, 15 and 16 corresponding, respectively, to the magazines 3, 4 and 5. The frame 2 adjacent to the notch, recess or depression 14 is formed with a guard 17 which limits the rearward shifting movement of the magazines and forms a support about which the magazine carrying frame with the magazines therein may swing from the normally forwardly and downwardly inclined position, as shown in Figs. 1 and 3, into the rearwardly and downwardly inclined position, as shown in Fig. 4, in which latter position the magazines are in position for removal. An abutment 18 may also be provided adjacent to the notch, recess or depression 16 to limit the forward shifting movement of the magazines.

The magazine carrying frame 2 is extended downwardly and forwardly to a point in proximity to the forward ends of the magazines and is adapted to rest upon the frame of the machine to properly position the escapements of each magazine in coöperative relation with the escapement actuating means. As shown in the present instance, the main frame of the machine has at each side a surface 19, and the magazine carrying frame has at each side a surface 20 adapted to ride on the respective surface 19 of the frame as the magazine carrying frame is shifted to bring the desired magazine into operative position. The surface 20 of the magazine carrying frame is provided with a suitable number of appropriately positioned seats adapted to rest on the surface 19 of the main frame, according to the particular magazine which is brought into operative position. In the present instance, there are three of these seats 21, 22 and 23, corresponding, respectively, to the magazines 3, 4 and 5 and to the notches, recesses or depressions 14, 15 and 16.

Owing to the movement of the magazine carrying frame in a forward and rearward direction, it is necessary to provide escapement actuating means which will clear the magazines during the shifting operation and which will be brought into operative position when any one of the magazines is positioned for use. In the construction shown, a series of supplementary reeds 24 is provided, these reeds being in effect sections of the reeds 7, they corresponding therewith in number and being arranged to register therewith when in operative position. These supplementary reeds are carried by a guide 25 which guide is adapted to swing about a supporting pivot or center 26, the supplementary reeds being shown swung into inoperative position in Fig. 2, and when they are in operative position,

they are in alinement and coöperative relation with the reeds 7.

The present invention provides means for swinging the supplementary reed into inoperative position and for shifting the assembler entrance downwardly or into a position to clear the magazines, preparatory to shifting of the magazines. The construction shown in the present instance for accomplishing this purpose comprises a shaft 27 which is pivoted in a suitable part of the main frame of the machine and carries a crank or arm 28 which is operatively connected to the supplementary reed guide 25, this shaft 27 also carrying a crank or arm 30, 75 which is operatively connected to the assembler entrance 8. An actuating arm 30 is also fixed to the shaft 27, it having a projection 31 thereon. The magazines are shifted in the present instance by an arm 32 which is pivoted on the main frame of the machine, at 33, and is connected to the magazine carrying frame by a link 34. A handle 35 constitutes a continuation of the arm 32 and it carries a grip 36 which is 80 pivoted to the handle, at 37, and is provided with a curved extension 38 which is arranged to act upon the projection 31 of the arm 30 when the grip 36 is pressed toward the handle. Fig. 2 shows the grip 36 pressed toward the magazine shifting handle 25, the arm 30 being shifted toward the left, causing the crank arm 28 to swing the supplementary reeds into inoperative position and causing the arm 29 to lower the 100 assembler entrance against the action of the spring 10. With the supplementary reeds and the assembler entrance shifted into the positions shown in Fig. 2, the magazines may be shifted by manipulation of the handle 35 to bring any desired magazine into operative position. When the desired magazine has reached operative position, the pressure upon the grip 36 is relieved, the spring 10 then acting to automatically raise the assembler entrance 8 into coöperative relation with the magazine in operative position, and this spring 10 acting through the assembler entrance, the arm 29, the shaft 27, and the arm 28 will also automatically swing the 105 guide 25 to bring the supplementary reeds into coöperative relation with the reeds 7 and the escapements of the particular magazine in use. From the foregoing it will be clear that the grip 36 which controls the 110 position of the supplementary reeds and the assembler entrance may be conveniently actuated by pressure of the hand of the operator in grasping the handle 35 preparatory to shifting the magazines by this handle, 115 and that removal of the hand from the magazine shifting handle will permit the spring 10 to automatically bring the assembler entrance and the supplementary reeds 120 into operative positions. 125 130

In order to remove one or more of the magazines from the magazine carrying frame, and to insert one or more other magazines containing different fonts of matrices, the magazine carrying frame is shifted to bring the foremost notch, recess or depression 14 into engagement with the corresponding roller 12, and the rear portion of the magazine carrying frame is provided with a handle 39 which may be grasped and pulled downwardly by the operator in rear of the machine, the magazine carrying frame being then caused to swing about the pivot 11 as a center, rocking the magazine carrying frame and the magazines from a forwardly and downwardly inclined position into a rearwardly and downwardly inclined position, as shown in Fig. 4. Any one of the magazines may then be withdrawn from the magazine carrying frame and another magazine inserted.

I claim as my invention:—

1. In a typographical machine, the combination with a relatively shiftable magazine carrying frame, of an assembler entrance adapted to receive matrices from any one of the magazines in use and reciprocable in an endwise direction transversely to the shifting movement of the magazine carrying frame, and means for shifting said assembler entrance into a position to clear the magazines preparatory to shifting of the latter.

2. In a typographical machine, the combination with a magazine carrying frame shiftable in a direction forwardly and rearwardly of the machine, of an assembler entrance having means for shifting it vertically in an endwise direction transversely to the direction of movement of the magazine carrying frame.

3. In a typographical machine, the com-

bination with a magazine carrying frame shiftable in a direction forwardly and rearwardly of the machine, and means for shifting the magazine carrying frame, of an assembler entrance reciprocable in an endwise direction transversely to the direction of movement of the magazine carrying frame, and means combined with the means for shifting the magazine carrying frame for shifting the assembler entrance preparatory to shifting the magazine carrying frame.

4. In a typographical machine, the combination with a magazine carrying frame shiftable to bring different magazines therein into operative position, and a handle for shifting said frame, of an assembler entrance shiftable vertically in an endwise direction to and from operative relation with any one of said magazines, and a grip associated with said handle and operatively connected to the assembler entrance for shifting the latter.

5. In combination, a plurality of inclined magazines, each having a series of escapements mounted thereon, a set of escapement actuating rods or bars, a set of supplementary escapement actuating rods pivoted to swing to and from operative position between said escapement actuating rods and the magazine escapements, an assembler entrance for the magazines, means for shifting the magazines to bring any one of them into operative position, and means for swinging the supplementary escapement actuating rods to clear the shifting magazines.

In testimony whereof I have hereunto set my hand in presence of two subscribing witnesses.

SAMUEL E. SPERRY.
